UNITED STATES PATENT OFFICE.

HAROLD E. YARROW, OF SCOTSTOUN, SCOTLAND.

CIRCULATION OF WATER IN WATER-TUBE BOILERS.

Application filed December 15, 1919. Serial No. 344,804.

To all whom it may concern:

Be it known that I, HAROLD EDGAR YARROW, a subject of the King of Great Britain, residing in Scotstoun, Scotland, have invented certain new and useful Improvements Relating to the Circulation of Water in Water-Tube Boilers, of which the following is a specification.

The invention relates to means for increasing the circulation of the water in water tube boilers. For this purpose it has been previously proposed to increase the circulation through the whole set of tubes by a fan or propeller placed in a main circulating tube connected with the headers of the boiler or in a pipe leading to the water drum.

According to the invention, which relates to the type of boiler such as the Yarrow, in which nests of tubes connect the water drums with the steam and water drum, one or more propellers are arranged in the water drum so as to promote the upward circulation of the water in the more highly heated tubes of the nest and the downward circulation in the less heated tubes.

In the accompanying drawings Fig. 1 is an elevation and Fig. 2 a sectional plan of a boiler partly in section showing an arrangement according to the invention. Fig. 3 is a plan of a water drum showing a further modification. Fig. 4 is a sectional elevation of a water drum and Fig. 5 a section on the line 5-5 of Fig. 4 of another modification. The same reference characters are used for similar parts in all the drawings.

In the arrangement shown in Figs. 1 and 2, A is the steam and water drum, B one of the water drums, D is a propeller placed in the drum B, E is a motor driving the propeller D, and F a gland at the end of the drum through which the propeller shaft K passes. H is a firebrick screen placed at one end of the boiler between the steam drum A and a water drum B for the purpose of preventing some or all of the tubes to the right of the propeller from being exposed to the heat of the fire. The wall H is shown as extending half way from the end of the drum to the propeller D, but it may extend over the whole of this space. The propeller draws the water down tubes G disposed on its right and delivers it to the steam drum A by tubes G disposed on its left.

In the modification shown in Fig. 3, two propellers D', D² are provided; J', J² are partitions which screen off sections I', I² disposed at each end of the water drum B from the central portion. The circulation is down the tubes at the ends of the boiler and up the tubes in the central portion. The propellers are placed in the part of the drum furthest removed from the furnace side M. Holes in the partitions J', J² corresponding to the size and position of the propellers, allow the water to circulate from the section I', I² to the central portion of the drum B. As the tubes G on the furnace side M conveying the upward currents extend to the ends of the boiler, the sides N', N² of the partitions are inclined so that these tubes are supplied with water delivered by the propellers, so that the circulation caused by the propellers assists the convection currents set up in all the tubes conveying the upward currents.

In the modification shown in Figs. 4 and 5, a central partition O divides the water drum B longitudinally; there may be the same or a different number of tubes G on either side of the partition. One or more propellers D (two are shown in the example illustrated) rotate in apertures in the walls of the partitions and deliver water from the right hand and cooler side of the partition to the furnace side M and, consequently, induce a downward flow in the tubes G to the right of the partition and an upward flow in the tubes to the left.

Having thus described the nature of the said invention and the best means I know of carrying the same into practical effect, I claim:—

1. In a water tube boiler, a water drum and a steam and water drum placed at a higher level than said water drum, nests of tubes connecting said water drum with said steam and water drum, said nests of tubes being arranged along the longitudinal axis of said water drum, some of said tubes being nearer the source of heat than the others, a propeller placed in said water drum, a circulation produced by said propeller flowing up the more highly heated tubes and down the less highly heated tubes.

2. In a water tube boiler, a water drum and a steam and water drum placed at a higher level than said water drum, nests of tubes connecting said water drum with

said steam and water drum, said nests of tubes being arranged along the longitudinal axis of said water drum, a partition in said water drum separating the more highly 5 heated tubes from the less highly heated, said partition having an aperture and a propeller in said water drum adapted to produce a circulation through said aperture from one side to the other of said partition.

10 3. In a water tube boiler, a water drum and a steam drum, a central vertical longitudinal partition in said water drum, tubes connecting said water drum with said steam and water drum, those on one side of the

partition conveying an upward current of 15 water and steam and those on the other side of the partition conveying a downward current of water, said partition having an aperture, and a propeller situated in said aperture and adapted to assist the downward circulation in the tubes on one side of the aperture and the upward circulation in the tubes on the other side of the aperture.

In testimony whereof I have signed my 25 name to this specification.

HAROLD E. YARROW.
